UNITED STATES PATENT OFFICE.

HERBERT J. BRAGDON, OF CHICAGO, ILLINOIS, ASSIGNOR TO CHESTER A. TURBIN, OF MADISON, WISCONSIN.

SPRING WINDER AND THE LIKE.

Application filed May 28, 1928. Serial No. 281,180.

This invention has to do with improvements in spring winders and the like. The invention relates particularly to spring winders for hand operation and for the winding 5 of springs of various sizes. The main object of the invention is to provide a very simple and reliable machine, and one which shall be very rugged and durable, capable of easily winding springs of various diameters and 10 made from various sizes of wire within the capacity of the machine.

Another object of the invention is to provide a machine which can be very easily changed so as to wind springs of different diameters. In this connection the change in 15 the diameter of the spring is produced by the substitution of a different arbor of proper size. The machine is so constructed that the arbors can be very easily set into place and 20 connected to the operating handle.

Another object is to provide an improved tensioning device for regulating the amount 25 of tension exerted on the wire as the same is drawn up onto the arbor or mandrel. This tension device includes hardened steel die plates the pressure between which may be readily regulated by a hand screw or wheel. The arrangement is such that if desired, and 30 from time to time, different or renewal die plates can be substituted without difficulty. Other objects and uses of the invention will appear from a detailed description of the 35 same which consists in the features of construction and combinations of parts herein-after described and claimed.

In the drawings:

Figure 1 shows a top view of a machine embodying the features of the invention, this 40 view being partly in perspective so as to better show the construction of the machine. In Fig. 1 the presser bar is being used so as to wind a loose turn spring such as is used for compression springs;

Fig. 2 shows a fragmentary view similar to 45 that of Fig. 1 showing the presser bar disengaged so that the machine will naturally and automatically wind a tight spring in which the convolutions are normally close together as in the case of a tension spring;

Fig. 3 shows a vertical section through the 50 machine of Fig. 1, the same winding a loose turn spring;

Fig. 4 shows an end view of the machine of Fig. 3 with the operating handle removed

and may be considered as a vertical section on 55 the line 4—4 of Fig. 3 looking in the direction of the arrows;

Fig. 5 shows a side elevation of a short section of loose turn spring; and

Fig. 6 shows a side elevation of a short 60 section of tight wound spring.

The machine includes a base block or member 7 having along its upper portion a horizontal V-shaped recess or trough 8. This is established by the side flanges 9 and 10, which, 65 as shown in Fig. 4, extend at an angle of substantially 45° with respect to each other. The flange 10 is substantially vertical and the flange 9 reaches outwardly at an angle thereto.

The flange 10 preferably constitutes a direct upward extension from the base block 7. The flange 9 which reaches outwardly at an angle is preferably reinforced by the end webs 11 and 12 constituting the end portions 70 of the base block itself. Said base block is also provided with the bottom or floor portion 13 which rests on the work bench or table or other support to which it may be connected in any convenient manner as by means of 75 screws 14.

The horizontal V-shaped recess is intended 80 for the accommodation of the winding arbor 15. The same constitutes a section of steel or other hard rod of diameter depending on 85 the size of the spring which is to be wound. This rod is rotated in any convenient manner as by means of a crank 16 having the handle 17, said crank being also provided with a relatively large opening 18 at its other 90 end which opening accommodates the end portion of the rod. A set-screw 19 is extended across the opening 18 so as to clamp the rod in place. By making the opening 18 of 95 large size it is capable of accommodating arbors of various diameters within the capacity of the machine.

The arbor is laid along the V-shaped opening 8. In order to give a better journal support for the arbor the side flanges 9 and 10 are preferably cut back in their central portions so as to leave the end bearing faces 20, 21, 22 and 23 which directly receive the contact of the arbor itself.

At the crank end there is an adjustable 100 bearing support for the arbor. The same includes a V-shaped member 24 which is carried by a stud or tap screw 25 which threads

into the end of the base block 7 as best shown in Figs. 3 and 4. This member 24 has the upwardly reaching flanges 25 and 26 set on a V angle with respect to each other and corresponding to the flanges 9 and 10 of the body block 7. The stud 25 is so positioned that the flanges 25 and 26 come into line with the flanges 9 and 10 as shown in Fig. 4.

The block 24 is also provided with an inwardly reaching rectangular lug 27. A U-shaped strap-iron section 28 having the downwardly depending arms 29 and 30 is set over the lug 27, and said strap is somewhat wider than the depth of the lug 27 so that when the stud 25 is tightened up the strap arms 29 and 30 will be solidly clamped against the body block 7.

The arrangement is such that when the arbor has been set into place beneath the U-shaped strap 28, said strap may be pulled down against the arbor to establish a top bearing for it, whereupon the stud may be tightened up.

By the foregoing arrangement it is possible to readily accommodate and give proper bearing support for arbors of different sizes within the capacity of the machine.

At the other end of the body block 7 there is an outwardly projecting boss 31. A threaded pin 32 reaches out from the end of said boss and a hand-wheel 33 is threaded thereon. A pair of hard steel plates 34 and 35 are set onto the stud 32 and can be clamped towards each other under any desired pressure by the hand-wheel 33. The stud 32 is perforated in a generally vertical direction as shown at 36 so that the spring wire 37 may be passed up through said perforation to the arbor. In passing through said perforation 36 the spring wire also passes between the hard plates 34 and 35 by which it is clamped at that point.

The end of the arbor is transversely slotted as shown at 38 in Figs. 1, 2, and 3. At the beginning of the operation the spring wire is passed up through the perforation 36 and through the end slot 38 of the arbor, and then the hand-wheel 33 is tightened up to give the desired amount of tension to the wire. Upon rotation of the handle and crank the wire will pull down on the projecting end of the arbor, but due to the adequate bearing support which the arbor receives the wire will be drawn up and wrapped around the arbor and this operation will continue as long as the arbor is rotated. With this arrangement a tight spring such as shown in Figs. 2 and 6 will be produced since the successive convolutions will press against each other and the arbor will be drawn lengthwise as it rotates.

In case it be desired to produce an open turn spring such as shown in Figs. 1, 3 and 5 for a compression spring, use may be made of a lever 39 which is pivoted to a finger 40

on the upper end of the boss 31, by means of a stud 41. The lever 39 can thus be rocked about the stud 41 as a vertical axis.

The end 42 of the lever will then press against the upwardly extending reach of the wire as clearly evident from Figs. 1 and 3 so that the wire may be pressed over, and then as the arbor is rotated and moved endwise the successive convolutions will form an open turn spring. When the lever 39 is not being used it is turned back more or less into the position of Fig. 2 where it is out of the way.

After the proper length of spring has been wound the arbor may be given a few backward turns so as to loosen up the spring convolutions therefrom. Thereupon the arbor can be easily drawn out from the spring and the latter can be cut off from the continuous wire length.

While I have herein shown and described only a single embodiment of the features of my present invention still I do not intend to limit myself thereto except as I may do so in the claims.

I claim:

1. A machine for the purpose specified comprising in combination a body member having a horizontally extending V-shaped opening for the accommodation of an arbor, a V-shaped block at one end of said body member, means for drawing said V-shaped block firmly towards the body member, a U-shaped strap metal bearing member located between the V-shaped block and the body member and of width to be clamped firmly between said parts and serving to establish a top arbor bearing, means for rotating the arbor so supported, a horizontally projecting stud on the body member at the other end thereof and beneath the V-shaped opening, a pair of hard metal washers on said stud, the stud being perforated intermediate between the washers to accommodate the spring wire, a hand-wheel threaded onto the stud to bind the washers towards each other at the position of the perforation, a sidewise projecting lug above the position of the stud and adjacent to the V-shaped opening, and a control lever pivoted on said lug to swing in a horizontal plane, substantially as described.

2. A machine for the purpose specified comprising in combination a body member having a horizontally extending V-shaped opening for the accommodation of an arbor, a V-shaped block at one end of said body member, means for drawing said V-shaped block firmly towards the body member, a U-shaped strap metal bearing member located between the V-shaped block and the body member and of width to be clamped firmly between said parts and serving to establish a top arbor bearing, means for rotating the arbor so supported, a horizontally projecting stud on the body member at the other end

thereof and beneath the V-shaped opening, a pair of hard metal washers on said stud, the stud being perforated intermediate between the washers to accommodate the spring wire, 5 and a hand-wheel threaded onto the stud to bind the washers towards each other at the position of the perforation, substantially as described.

3. A machine for the purpose specified comprising in combination a body member having a horizontally extending V-shaped opening for the accommodation of an arbor, a rest block at one end of the body member, a U-shaped strap metal bearing member located between the rest block and the body member, means for drawing the rest block towards the body member to thereby clamp the bearing block in place, an arbor resting in the V-shaped opening and through the bearing block, means for rotating the arbor so supported, a horizontally projecting stud on the other end of the body member and beneath the V-shaped opening, suitable clamping washers thereon, and means for drawing the washers together to thereby clamp the wire between them, substantially as described.

4. A machine for the purpose specified comprising in combination a body member having a horizontally extending V-shaped opening for the accommodation of an arbor, means for supporting and rotating one end of the arbor located therein, a horizontally projecting stud at the other end of the device and beneath the position of said opening, a pair 35 of clamping washers thereon, means for drawing said washers together to thereby clamp the wire between them, a lever having one end located at the path of travel of the wire moving from the clamping washers to the arbor, and a pivotal support for said lever 40 on the body block, whereby said lever may be used to deflect the wire sidewise during its travel from the clamping washers to the arbor, substantially as described.

45 5. A machine for the purpose specified comprising in combination a body member having a horizontally extending opening with open bearings at both ends thereof, both of said bearings having their open sides facing in the same general direction, an arbor located in and supported upon said open 50 bearings, a driving crank secured to one end

of said arbor, removable means for retaining the arbor within the bearing closest and adjacent to said crank, the arbor overlying the device beyond the other open bearing, a wire tension device secured to the bearing member at the side thereof away from the direction of the opening of the bearings thereof, whereby the wire running from said tension device up onto the overhanging portion of the arbor tends to draw the arbor into the adjacent open bearing, and a lever pivoted in position to engage the wire at a point intermediate between the tension device and the overhanging portion of the arbor, substantially as described.

6. A machine for the purpose specified comprising in combination a body member having a horizontally extending opening with open bearings at both ends thereof, both of said bearings having their open sides facing in the same general direction, an arbor located in and supported upon said open bearings, a driving crank secured to one end of said arbor, removable means for retaining the arbor within the bearing closest and adjacent to said crank, the arbor overlying the device beyond the other open bearing, a wire tension device secured to the bearing member at the side thereof away from the direction of the opening of the bearings thereof, whereby the wire running from said tension device up onto the overhanging portion of the arbor tends to draw the arbor into the adjacent open bearing, substantially as described.

7. A machine for the purpose specified comprising in combination a body member, a pair of bearings therein longitudinally separated from each other, both of said bearings being open in the same general direction, an arbor located in and supported upon said open bearings, a driving crank secured to one end of said arbor, removable means for retaining the arbor within the bearing closest and adjacent to said crank, the arbor overlying the body member beyond the other open bearing and adapted to receive a wire winding upon the overlying portion of the arbor, together with means for tensioning said wire and drawing the arbor to its seat in said open bearing, substantially as described.

HERBERT J. BRAGDON.
